UNITED STATES PATENT OFFICE.

SAMUEL BUTTERWORTH, OF EVERETT, MASSACHUSETTS, ASSIGNOR OF ONE-HALF TO
CHARLES W. AIKEN, OF BROOKLYN, NEW YORK.

CLOTHES-DRIER.

1,109,279.

Specification of Letters Patent.

Patented Sept. 1, 1914.

Application filed January 5, 1914. Serial No. 810,389.

To all whom it may concern:

Be it known that I, SAMUEL BUTTERWORTH, a citizen of the United States, and a resident of Everett, in the county of Middlesex and State of Massachusetts, have invented certain new and useful Improvements in Clothes-Driers, of which the following is a specification.

This invention relates to clothes driers which are used indoors and it has for its object to provide a drier adapted to be securely supported at different distances from the wall of a room, either projected in an operative position from the wall or retracted to a position in close proximity to the wall.

The invention consists in the improvements which I will now proceed to describe and claim.

20 Of the accompanying drawings:—Figure 1 represents a side elevation showing a drier embodying my invention supported in its operative position. Fig. 2 represents a top plan view of the drier head and the inner portions of the arms. Fig. 3 represents a section on line 3—3 of Fig. 2. Fig. 4 represents an edge view of the head and arms as shown by Fig. 2. Fig. 5 represents a section on line 5—5 of Fig. 3. Fig. 6 represents a view similar to Fig. 3 showing some of the arms folded. Figs. 7 and 8 represent fragmentary sectional views herein-after referred to. Fig. 9 represents a front elevation of the drier in its retracted position. Fig. 10 represents a view similar to Fig. 1, showing the drier in its retracted position. Fig. 11 represents an enlargement of a portion of Fig. 10. Fig. 12 represents a section on line 12—12 of Fig. 11. Fig. 13 represents an enlargement of a portion of Fig. 9. Fig. 14 represents a section on line 14—14 of Fig. 9. Fig. 15 represents a section on line 15—15 of Fig. 14. Fig. 16 represents a section on line 16—16 of Fig. 14.

45 The same reference characters indicate the same parts in all the figures.

My improved drier comprises a vertical standard which is preferably telescopic and includes a lower tubular member 12 and an upper member 13 slidable vertically in the lower member and provided at its upper end with a head hereinafter described, and with drier arms 14 engaged with said head, the arms being adapted to be supported 50 radially in their operative positions and

dropped or folded to vertical positions in close proximity to the standard.

The numeral 15 represents a runner which is movable vertically on the standard member 12 and is preferably compressible so that it may be firmly secured to the standard at different heights, said runner being preferably composed of two sections as shown by Fig. 12, united at one side of the standard by bolts or rivets 16 and adjustably connected at the opposite side of the standard by a screw threaded pin 17 passing through ears 18 and 19 on the runner sections, said pin being provided with a handle 20 whereby it may be turned to expand and contract the runner, and with an enlargement 21 forming a shoulder adapted to press the ear 19 against the ear 18. The enlargement 21 may be formed by one or more nuts screwed upon the pin 17, two nuts being here shown one of which serves to lock the other. The ear 18 has a threaded orifice engaging the thread on the pin 17. The orifice in the ear 19 is not threaded, hence, the operation of turning the pin 17 causes a movement of the pin and its enlargement 21 relative to the ears 18 and 19 and expands or contracts the runner 15. The runner ear 18 is extended to form a hinge member which is connected by a hinge pin 22 with a hinge ear 23 formed on or attached to a cross bar 24. To said cross bar are attached by bolts 25 the inner ends of two diverging braces 26. To the outer ends of said braces are hinged or pivoted at 27 two terminals each composed of a hinge ear 28 and a plate 29 adapted to be screwed to a suitable support such as a base board 30 forming a part of the wall of a room. The standard member 12 is provided with a foot 31 adapted to slide on a floor and preferably provided with antifrictional rollers 32.

When the runner and the braces are adjusted as shown by Fig. 1, the standard is firmly supported in a projected position far enough from the wall of the room to permit all of the drier arms 14 to radiate from the standard. The standard may be retracted toward the wall of the room as shown by Figs. 9 and 10, the runner 15 being moved upwardly on the standard until the braces 26 are approximately vertical. When this is done, the drier arms 14 at the inner side of the standard are dropped or folded as indicated at the left of Fig. 10 and the

other arms may, if desired, retain their radial positions so that about one-half of the arms may be utilized when the standard is retracted. The hinge ears 18 and 23 5 may be locked together by the hinge pin 22, said pin being provided with a handle 33 and with an enlargement 34 bearing on the hinge ear 23. The threaded portion of the hinge pin 22 engages a threaded orifice 10 in the ear 18 and passes through an unthreaded orifice in the ear 23 so that the rotation of the pin is adapted to press the ears 18 and 23 so closely together that the hinge is practically locked. When the hinge 15 ears are thus locked together and the runner is contracted, relative movement of the standard and braces is prevented and the standard may be firmly held in its projected and retracted positions, the hinge being unlocked and the runner expanded before moving the standard from either position. The tubular standard member 12 is provided 20 near its upper end with a slot 38 (Fig. 14) through which project teeth on a spur gear 39 journaled on a stud 40 attached to an ear 41 on the standard member 12. The sliding standard member 13 is provided with a series of recesses 42 (Fig. 14) these forming 25 the equivalent of a series of rack teeth engaged by teeth of the spur gear 39. Said gear may be locked to maintain the standard member 13 at different heights by means 30 of a dog 43 pivoted at 44 to the ear 41, and having a handle 45. The head which supports the drier arms 14 comprises a hub 46 (Fig. 3) journaled to rotate on the upper 35 end of the standard member 13, and provided with means for engaging the inner ends of the arms 14, and a top plate 47 attached to and overhanging the hub and provided with means for supporting the drier arms horizontally. The hub 14 has a horizontal web 48 and a vertical flange 49 40 formed on the margin of said web. In the flange 49 are formed a series of vertical slots 50 which are extended horizontally 45 into the web 48 as clearly shown by Figs. 3 and 8. The top plate 47 is secured by screws 51 to hollow studs 52 on the web 48, said top plate projecting outwardly from the flange 49 and being raised above said flange 50 as indicated by Figs. 3, 7 and 8.

On the under side of the top plate 47 is formed an annular rib 53 which is of greater 55 diameter than, and concentric with, the flange 49. To the top plate 47 are attached radial wire fingers 54 by means of rivets 55 engaging bends formed on said fingers as 60 shown by Fig. 2, the inner ends of the fingers being bent inwardly and inserted in sockets formed for their reception in the top plate 47. The outer ends of the fingers 54 are bent to form downwardly projecting hooks or rests 56. By reference to Fig. 3, it 65 will be seen that each arm 14, when in its

operative position, bears at its lower edge on one of the rests 56 and at its upper edge on the rib 53, the inner end of the arm projecting through a slot 50 and being provided with oppositely projecting ears 57 70 (Fig. 8) adapted to bear on the inner side of the flange 49 and on the upper side of the web 48.

When the arms 14 are adjusted horizontally, they are prevented from moving endwise outwardly by the ears 57 and are supported against downward movement by the rests 56 and rib 53. Each arm 14 may be folded or dropped to a vertical position beside the standard by swinging it upwardly 80 out of the rest 56 which supports it, and then laterally away from said rest, and then downwardly to a vertical position in which it is supported by the bearing of the ears 57 on the upper side of the web 48 as indicated at the left of Fig. 6. Each arm 14 is preferably made of galvanized sheet metal, the blank from which the arm is made being bent into the U shape illustrated by Figs. 7 and 8.

The above described head is of simple construction and permits quick movement of the drier arms to and from their operative positions.

I claim:

1. A clothes drier comprising a standard having a sliding foot, a head on said standard having radiating drier arms, a runner movable vertically on said standard, and braces hinged to said runner and provided with means for engaging a fixed support, the braces and runner being adjustable to support the standard either in a projected or a retracted position, and the drier arms being foldable to permit the retraction of the standard.

2. A clothes drier comprising a standard having a sliding foot, a head on said standard having radiating drier arms, a runner movable vertically on said standard, and braces hinged to said runner and provided with means for engaging a fixed support, the braces and runner being adjustable to support the standard either in a projected or a retracted position, means being provided for preventing relative movement of the braces and runner and holding the standard in either position.

3. A clothes drier comprising a standard having a sliding foot, a head on said standard having radiating drier arms, a runner movable vertically on said standard, and provided with means whereby it may be locked thereto, a pair of diverging braces connected at their inner ends, a hinge connecting the connected ends of the braces with the runner, and having means whereby it may be locked, and terminals hinged to the outer ends of said braces and adapted to be attached to a fixed support, the braces

and runner being adjustable to support the standard either in a projected or a retracted position, the hinge, when locked, and the runner when confined on the standard, holding the standard in either position.

4. A clothes drier comprising a standard having a sliding foot, a head on said standard having radiating drier arms, a compressible runner movable on said standard and having means whereby it may be compressed and confined thereon, said runner having a hinge ear, a complemental hinge ear pivoted to the runner ear and having a cross bar, diverging braces, attached at their inner ends to said cross bar and having hinged terminals at their outer ends adapted to be attached to a fixed support.

5. A clothes drier comprising a standard having a sliding foot, a head on said standard having radiating drier arms, a runner 20 movable on said standard and provided with a hinge ear, a brace-carrying cross bar having a hinge ear pivoted to the runner ear, means being provided for locking said hinge ears together, and diverging braces attached 25 at their inner ends to said cross bar and having hinged terminals at their outer ends adapted to be attached to a fixed support.

In testimony whereof I have affixed my signature, in presence of two witnesses.

SAMUEL BUTTERWORTH.
